Primary Examiner — Sandra Morris(74) *Attorney, Agent, or Firm* — John V. Daniluck; Bingham Greenebaum Doll LLP(57) **CLAIM**

The ornamental design for a bottle, as shown and described.

DESCRIPTION

FIG. 1 is a top, front, left side perspective view of a bottle showing my new design, with portions of the rounded shoulders being transparent, the broken lines forming no part of the claimed design;

FIG. 2 is a front elevational view of the bottle of FIG. 1, the rear elevational view being identical;

FIG. 3 is a left side elevational view of the bottle of FIG. 1, the right side elevational view being identical; and

FIG. 4 is a top plan view of the bottle of FIG. 1.

FIG. 5 is a top, front, left side perspective view of a bottle showing my new design, with portions of the rounded shoulders not being transparent, the broken lines forming no part of the claimed design;

FIG. 6 is a front elevational view of the bottle of FIG. 5, the rear elevational view being identical;

FIG. 7 is a left side elevational view of the bottle of FIG. 5, the right side elevational view being identical; and,

FIG. 8 is a top plan view of the bottle of FIG. 5.
